UNITED STATES PATENT OFFICE.

JOHN N. COUGHLAN, OF NEW YORK, N. Y.

PROPELLED ATTACHMENT FOR BOATS.

Application filed June 5, 1923. Serial No. 565,855.

To all whom it may concern:

Be it known that I, JOHN N. COUGHLAN, a citizen of the United States, and a resident of the city of New York, borough of 5 Manhattan, in the county and State of New York, have invented a new and Improved Propelling Attachment for Boats, of which the following is a full, clear, and exact description.

10 This invention relates to an attachment for boats, and has for an object the provision of means whereby a person can very readily operate the boat by means of a propeller which is connected with a frame or support readily applied to and removed from the boat structure at will. This frame contains all the necessary elements for propelling and steering the boat without requiring any alteration of the boat structure.

20 Another object resides in the provision of a propelling attachment which is especially simple and compact and readily portable.

A further object resides in the particular construction and arrangement of parts 25 which are hereinafter described and claimed and shown in the accompanying drawings.

The invention is illustrated in the drawings, of which—

Figure 1 is a longitudinal vertical section 30 taken through the end of the boat and through the portable unit.

Figure 2 is a section taken on the line 2—2 of Fig. 1.

The form of the invention shown in the 35 drawings is a preferred form, although it is understood that modifications in the construction and arrangement of the parts and in the character of the materials used may be adopted without departing from the spirit 40 of the invention.

As shown in the drawings, the invention includes a boat having a bottom 1 and a rear or transom 2 at the intersection of which a block or base portion 3 is disposed. The 45 unit which I attach to the boat for the purpose of propelling the same comprises a bearing portion 4 through which a shaft 5 extends. This shaft has on its end pinions 6 and 7. To one end of the bearing 4 a vertical plate 8 is disposed, the lower end of which is flanged as at 9 and connected by any suitable means to the bottom or interior 50 of the boat, preferably the base block 3. To the other end of the bearing portion 4, which 55 rests on the top edge of the transom 2, I connect a U-shaped frame, one leg 10 of

which extends downwardly adjacent the rear face of the transom 2 and has fastened thereto a plate 11 extending transversely to the leg 10 and having at opposite ends sleeves 60 12 and 13 through which bolts 14 extend to fasten the ends of the plate 11 against the transom, thereby disposing the U-shaped frame, of which leg 10 is a portion, rigidly with respect to the boat. The U-shaped 65 frame is provided with a base portion 15 and a second leg 16 parallel to the leg 10. This second leg 16 is rigidly spaced from the leg 10 by brace members 17 and 18 extending therebetween. The end of shaft 5 70 is journaled in the upper end of the leg 16. A propeller shaft 19 is journaled at opposite ends in the legs 10 and 16 and controls a propeller 20, preferably a four-bladed propeller. A pinion 21 is mounted on the shaft 75 19 and is connected to the pinion 7 by chains 22. The upper end of the leg 16 is flared outwardly and rearwardly and constitutes a portion 23 to receive the upper end of a rudder shaft 24 provided at its upper end 80 with a manually operable device, such as a wheel 25, and along its lower end with a rudder 26. The lower end of the rudder shaft 24 is suitably fastened to the end of a curved bracket plate 27 fastened as at 28 85 by any suitable means to the base 15 of the U-shaped frame.

The pinion 6 meshes with a gear 29 which is mounted loosely on a shaft 30 one end of which is rotatably mounted on the plate 8. 90 A pinion 31 is connected rigidly to the gear 29 and is connected also to a handle portion 32, permitting the manual operation of the gear 29. The pinion 31 is adapted to permit the transmission of power to the gear 29 95 through other means than by manually operable means.

It is therefore observed that by moving the handle 32 power is transmitted through the gear 29, pinion 6, shaft 5, pinion 7, 100 chain 22, pinion 21, shaft 19, through the propeller 20. The engagement of the flange 9 and the plate 11 with portions of the boat firmly fastens the attachment to the boat. It is found that with a comparatively slight 105 effort the boat is propelled through the water in a much easier manner than by rowing. To remove the attachment from the boat, it is merely necessary to remove the bolts 14 and disconnect the flange 9 from the base 110 portion 3, which is preferably fastened thereto by a screw 33. It will, therefore, be

observed that in a very simple manner this device can be attached to and removed from a boat and that it contains all the necessary elements whereby the boat may be propelled and steered in one compact unit which can be very readily carried around. The application and removal of the unit from the boat involves substantially no change in the structure of the boat.

10 What I claim is:

A propelling attachment for boats, which comprises a bearing portion adapted to rest on the upper edge of the rear transom of a boat, a dependent plate on the front end 15 of the bearing portion fastened to an interior portion of the boat, a U-shaped frame connected to the rear end of the bearing portion, a transverse plate on the frame, means for fastening the transverse plate of 20 the U-shaped frame to the rear face of the transom, a driving gear supported on said

plate, a driving shaft extending through said bearing portion, a pinion on the front end of said shaft meshing with said gear, a pinion on the rear end of said shaft, the rear 25 end of said shaft being journaled in one part of the U-shaped frame, a driven shaft journaled in the U-shaped frame, a pinion on said shaft, a chain connecting the pinion on the driven shaft and the pinion on the 30 rear end of the driving shaft, a propeller on the rear end of the driven shaft, outwardly and rearwardly projecting bracket plates connected to the upper and lower ends of the U-shaped frame, a rudder shaft journaled 35 at its ends in said bracket plates, a rudder on said shaft, means for permitting the movement of said rudder, a pinion attached to said driving gear, and a handle attached to said pinion.

JOHN N. COUGHLAN
